UNITED STATES PATENT OFFICE

LERoy L. SALFISBERG, OF SOUTH ORANGE, NEW JERSEY

KEY CARRIER

Application filed April 29, 1930. Serial No. 448,187.

The subject-matter of the present invention is directed to key carriers adapted to support a plurality of keys.

Primarily, the object of the invention resides in the provision of an article of the above-mentioned character wherein a plurality of keys are arranged in frictional interrelationship, said relationship permitting of rotative movement of the keys or a key 10 when the latter is to be inserted in a lock.

Another object is to provide means whereby a plurality of keys may be arranged in cooperative relation to a base member in a manner to preclude displacement of a key, said 15 keys being held in any position to which they may be rotated.

Another object of the invention is to provide a flexible member to which any number of keys may be attached, said flexible member being adapted to be associated with a base plate to hold the keys in position and in a manner to permit convenient removal thereof when additional keys are added to said member.

25 A further object is the provision of a hinged clamping member adapted to be latched in a position to firmly anchor said flexible member against said base plate.

Another aim of the invention is to produce an article wherein the keys are held in a flexible but firm manner so that when one of the keys is inserted in the lock of an automobile, for instance, the ignition lock, the companion keys will not rattle about to the 35 detriment of the finish of the instrument board of said machine.

As will presently appear the device is adapted to receive keys that may be assembled therewith to present the teeth thereof 40 up or down so that they are always in position to be inserted in a lock, said keys being capable of arrangement thereon whereby the sense of feeling may locate a desired key.

The invention is further featured by the 45 provision of a base plate which may be finished to preclude tearing of the pocket of the user, said base plate being capable of receiving advertising thereon, whereby it may find use as a novelty token by automobile firms, 50 or accessory houses, and as said base plate

may be finished in attractive colors, it becomes a thing of beauty appealing to a certain extent to the public at large.

With these and other objects in view, together with others which will appear as the 55 description proceeds, the invention resides in the novel formation, combination, and arrangement of parts, all as will be described more fully hereinafter, illustrated in the drawings, and particularly pointed out in the 60 claims.

In said drawings:

Figure 1 is a side elevation of my novel 65 and improved key carrier showing the keys nested beneath the base plate.

Fig. 2 is a plan view thereof, the dot and dash indication showing a key rotated from the carrier.

Fig. 3 is a sectional view on the line 3—3 of Fig. 2.

Fig. 4 is a plan view of the base plate 70 per se.

Fig. 5 is a sectional view thereof taken on the line 5—5 of Fig. 4.

Fig. 6 is a detail view of a clamping member.

Fig. 7 is a plan view thereof.

Fig. 8 is a view showing a hinged member prior to its forming to pivotally connect the clamping member to said base plate.

Referring now more in detail to the accompanying drawings, let 10 denote the base plate of my novel key carrier which may be constructed of metal, bakelite, or similar material, and which will be proportioned to receive a plurality of keys generally indicated by the numeral 11, in Fig. 1. The particular construction of said base plate will be clearly understood on inspection of Figs. 4 and 5, wherein it will be observed that I have 80 provided an enlargement 12 on its upper surface as viewed in Fig. 4, said enlargement being provided with recess 13 which extends to an aperture 14, that portion of said recess adjacent said aperture being slightly 85 deepened, as indicated at 15, for the reception of a hinged member, about to be described. As shown in Fig. 5 said recess 13 is provided with a groove 16, which is supplied with spiral ridges 17, one end of said groove 90

80

85

90

95

100

16 terminating at the opening 18 extending to the bottom surface of said base plate 10. Said base plate 10 is also provided with a slot 19, adjacent said opening 18, and it will be noted that said slot 19 extends from one end of said recess 13 to the lower surface of said base plate, as clearly shown in Fig. 5.

As explained hereinbefore, it is proposed to provide a key carrier whereby a plurality of keys may be held in a pre-arranged order and whereby said keys may be rotatively supported on a base plate and frictionally held in assembled positions thereon. Further, means is provided whereby a definite number of keys may be associated with a base plate, said number of keys being capable of variation, as desired, and said definite number being held in close assembled relation with said base plate.

20 The key-retaining means is composite in structure and comprises a resilient or spring member 20, one end thereof being fixedly secured to the threaded shank 21 of the button 22, as shown in Fig. 3, the medial portion 25 thereof being normally insertible within the usual apertures in the keys 11, while a disk 23 abuts a contiguous key, said disk being provided with an inturned flange, or peripheral flange 24 within which is anchored the 30 lower convolution of a spring 25 interposed between said button 22 and said disk 23, as clearly shown in Figs. 1 and 3.

The clamping member heretofore referred to is designated by the numeral 26, said member being substantially U-shaped in cross-section and having a slot 27 arranged at its inner end for the reception of one leg 28 of a hinge member 29. As shown in Fig. 8, the hinge member is formed by a single piece of 40 material adapted to be bent to the form shown in Fig. 3, one leg 28, as aforesaid, passing through the slot 27 in said clamping member 26, said leg 28 and its companion 30 being insertible in slot 19 in said base plate 45 10, the extremities thereof being bent to fixedly anchor the same in place. In view of this arrangement said clamping member 26 is pivotally disposed with respect to said base plate and may be lowered to the position 50 shown in Fig. 3, or it may be swung upwardly after releasing certain latch means, as will presently appear.

Said latch means 31 in construction, is somewhat similar to the well-known eyelet, 55 in that the same is hollow and after insertion in the aperture 14, the lower portion thereof is flexed outwardly as shown in Fig. 3. However, the union of said latch means 31 and said aperture 14 is not sufficient to pre-60 clude free rotation of said means in said aperture. It will be noted that said latch means is provided with a lip 32 which is adapted to overlie the nose portion 33 of said clamping member 26.

65 Upon inspection of Figs. 1 and 3, it will

be observed that said clamping member 26 is in operative position, that is, the same is securely swung over said base plate in that the nose portion 33 thereof is positioned beneath the lip 32 of said latch means 31, and in this position said clamping means firmly binds the spring member 20 in the position shown in Fig. 3. It will be noted that said nose portion 33 fits into the deepened portion 15 of said recess 13. Obviously, a slight rotation of said latch means 31 removes the lip 32 out of engagement with the nose portion 33 of said clamping member 26 and the latter is free to be elevated on its pivotal connection.

Reverting now to the spring member 20, it will be noted that the series of keys 11 are now supported thereby, and assuming that said clamping member 26 has been elevated, as aforesaid, it is only necessary to insert said spring member through the opening 18 in said base plate 10, whereupon said member is bent slightly at right angles and the clamping member is swung downwardly until said spring member is engaged thereby. A continued depression of said clamping member bends said spring member to the position shown in Fig. 3 and as the nose portion 33 arrives within the deepened portion 15, said latch means is rotated until the lip 32 overlies said nose portion 33, whereupon the parts assume the position shown in said Fig. 3. The engagement of the several convolutions of said spring member with the ridges 17 in the groove 16 positively precludes the escape of said member, but this fixed relationship does not interfere with the free rotation of the keys or a selected key, since the resiliency of the spring 25 permits relative movements between the keys, and yet this movement is sufficiently restrictive to prevent a loose cooperation of the keys. In this way, rattling or other movement of the several keys is prevented.

When it is desired to remove a key, or to substitute an additional key, the clamping member is swung upwardly after releasing its nose portion from the lip 32 of the latch means 31. The spring member 20 may be withdrawn from the opening 18 and the operation completed. The replacement of said spring member is as aforesaid.

From the foregoing it is apparent that I have devised a key carrier wherein a base plate and a tensioning device holds the keys in any position to which they are rotated. In view of the flexible spring member 20 the keys are held to the base plate when bent at right angles and secured in ridges 17 by means of the clamping member, as aforesaid. Obviously, so long as the lip of the latch means maintains the position indicated in Fig. 2, there is no danger of the key carrier coming apart.

While the present is a disclosure of the

preferred embodiment of the invention, it is to be understood that the invention is not limited thereto, as various changes in the minor details of construction, proportion and arrangement of parts may be resorted to without departing from the spirit of the invention as defined in the appended claims.

5 I claim:

- 10 1. A key carrier comprising a base plate, resilient key-retaining means cooperating therewith, a clamping member hingedly borne by said plate and adapted to removably secure said key-retaining means to said plate and rotatable latch means coupling the free end of said clamping means to said plate.
- 15 2. A key carrier comprising a base plate having a groove, flexible key-retaining means adapted to fit in said groove, a clamping member hingedly borne by said plate and adapted to removably secure said key-retaining means in said groove and latch means adapted to removably secure the free end of said clamping means to said plate.
- 20 3. A key carrier comprising a base plate having a longitudinal recess and a groove having an opening at one end, resilient key retaining means insertible within said opening, a clamping member hingedly borne by said plate and adapted to fit in said recess to removably position said key-retaining means within said groove and rotatable latch means having a lip portion adapted to overlie the free end of said clamping means to position the same within said recess.
- 25 4. A key carrier comprising a base plate having a longitudinal recess and a groove having an opening at one end, flexible key retaining means insertible within said opening, and a clamping member hingedly borne by said plate and adapted to fit in said recess to removably position said key retaining means within said groove.

In testimony whereof I affix my signature.

45 LEROY L. SALFISBERG.
